UNITED STATES PATENT OFFICE.

EDWIN KENNETH NORTON, OF CANONSBURG, PENNSYLVANIA, ASSIGNOR TO CONTINENTAL CAN COMPANY, INCORPORATED, OF SYRACUSE, NEW YORK, A CORPORATION OF NEW YORK.

COMBINED FILLING AND CLOSING MACHINE.

1,273,651.

Specification of Letters Patent. Patented July 23, 1918.

Application filed December 5, 1916. Serial No. 135,107.

To all whom it may concern:

Be it known that I, EDWIN KENNETH NORTON, a citizen of the United States, residing at Canonsburg, in the county of Washington, State of Pennsylvania, have invented certain new and useful Improvements in Combined Filling and Closing Machines, of which the following is a description, reference being had to the accompanying drawing and to the figures of reference marked thereon.

The invention relates to new and useful improvements in devices for filling and closing cans, and more particularly to metal cans wherein the end of the can is seamed onto the body portion thereof for closing the can.

An object of the invention is to provide a machine of the above character wherein the cans may be filled, the ends placed thereon, and clenched or otherwise secured to the body of the can without moving the can laterally relative to the filling device.

A further object of the invention is to provide a combined filling and closing machine having a rotating carrier on which the empty cans are placed, together with means for filling the cans, placing the ends on the cans, and securing the ends to the can bodies while the cans are still on the carrier.

A still further object of the invention is to provide a device of the above character wherein the cans may be filled and closed during the continued movement of the carrier.

A still further object of the invention is to provide a device of the above character with a can end feeding mechanism which includes devices for marking the ends as they are fed to the carrier.

A still further object of the invention is to provide a combined filling and closing machine which includes a rotating carrier having a plurality of filling devices and a rotating support associated with each filling device, together with means for placing an empty can on each support, means for filling the cans on the supports during a partial rotation of the carrier, and means for placing a can end over each filled can, and also means for securing the can end onto the can body as the filled covered can is rotated.

These and other objects will in part be

obvious and will in part be hereinafter more fully disclosed.

In the drawings, which show by way of illustration one embodiment of the invention:

Figure 1 is a plan view showing, more or less diagrammatically, a machine embodying the improvements;

Fig. 2 is a view, partly in plan and partly in section showing the valves for the filling devices, the cam for operating the same, and also the can end feeding and marking device;

Fig. 3 is a vertical sectional view on the line *b*—*b* of Fig. 2;

Fig. 4 is a sectional view on the line *a*—*a* of Fig. 2;

Fig. 5 is a detail in vertical section showing one of the filling devices, the valve for controlling the same, the can end seat, and the rotating support for the can to be filled, the can having been filled and the can end placed on its seat;

Fig. 6 is a similar view, showing the support raised and the cover seated on the chuck ready to be engaged with the clenching mechanism;

Fig. 7 is a detail in section through one of the clenching rolls, showing the can end clenched to the can body;

Fig. 8 is a detail in vertical section, showing the stack and the means for feeding the can ends from the stack;

Fig. 9 is a detail, showing a stack lifting device separating the stack from the lowermost can end;

Fig. 10 is another view of the same;

Fig. 11 is a perspective view of the can end feeding disk and the can end support;

Fig. 12 is a detail showing the means for retarding the movement of the can end while it is marked;

Fig. 13 is a detail in section, showing the yielding finger for forcing the can end forward to marking position;

Fig. 14 is a vertical sectional view through the marking device;

Fig. 15 is a sectional view through one of the nozzles and the support for the filled can, showing a modified form of means for securing the can end to the can body while on said can body support;

Fig. 16 is a similar view, but showing the

can raised into engagement with the chuck; and

Fig. 17 is a detail showing the cam-shaped rail for raising and lowering the operating cam for the seaming rolls.

The invention consists broadly in a rotating carrier which is provided with a plurality of rotating supports each of which is adapted to receive an empty can. The cans

10 are fed onto the rotating support by suitable feeding mechanism, which times the cans so as to place them one after the other on the supports while the carrier is rotating. Directly above each can support is a 15 filling device, each of which includes a nozzle and a valve for closing the nozzle. These valves are operated by a suitable cam so that during a partial rotation of the carrier the valves will open, the can bodies 20 will be filled, and then the valves are closed. Also associated with the rotating carrier is a can end feeding and marking device. The can ends are taken from the stack and fed to the marking device, and then from 25 the marking device onto a can end seat which is located directly above the can on the rotating carrier. The can end is fed onto the seat after the can is filled and the valve is closed. The can body is then raised 30 through a tapered ring which centers the same and rounds up the can preparatory to receiving the can end and the can end is engaged by the can body and carried up against the chuck. This seats the can end 35 in the can body, and as the support is rotating the can body and can end, together with the chuck engaging the same, will rotate. The rotating can body with the can end seated therein is then brought into engagement 40 with the closing means for securing the can end to the can body. This in one form of the invention consists in a clenching device which operates to turn the edge of the can end underneath the flange 45 on the can body at a plurality of points. In another form of the invention, the can end is secured to the can body by double seaming rolls.

Referring more in detail to the drawings: 50 The improved filling and closing machine consists of a supporting base 1 on which is mounted a rotating carrier 2. This carrier is in the form of a table which is attached to a sleeve 3, and this sleeve 3 is rotated by 55 suitable means. The table has a series of openings 4 formed therein and in each opening is a support 5. The support 5 is mounted on a sleeve 6 and this sleeve 6 carries a gear 7 which meshes with a gear 8 60 formed in the base 1. The sleeve 6 is mounted so as to rotate and slide in a bearing formed at the outer end of an arm 9 carried by the central rotating sleeve 3 of the carrier. The sleeve 6 also has a rod extending therethrough which is connected to

a bracket 10 at its lower end, and this bracket carries a roller 11 which runs in a cam groove 12 in the supporting base 1. As the carrier 2 rotates, the gears 7 attached to each support will cause the supports to rotate, and the rollers 11 also attached to each support will raise and lower these supports, as will be hereinafter more fully described.

At the upper end of the sleeve 3 of the 75 rotating carrier there are a plurality of tanks 13, one for each support 5, and at the lower end of each tank there is a depending nozzle 14. This depending nozzle is formed with an inner sleeve 15, and an 80 outer sleeve 16. The outer sleeve 16 carries a rotatable chuck 17. There is a housing 18 around both of the sleeves, and ball bearings 19 are placed between this housing and the rotatable chuck 17. The housing 18 is also provided with a bracket 20 which extends downwardly from the head, and this bracket carries a plate 21 which is provided with a can end seat 22 formed around the upper edge of an opening 23 85 through the plate. The lower edge of this opening is tapered as at 24. Extending downwardly from the plate is a guiding segment 25. This guiding segment is adapted to receive the empty can when it is 90 placed on the rotating support and centers the same underneath the head.

Each nozzle is provided with a slide valve 95. The valve carries a roller 27 which is adapted to engage a cam groove 28 in a fixed 100 plate 29. The chuck 17 extends a slight distance below the flange at the lower end of the sleeve 15 and when the rotating support is raised the chuck will engage the can end, seat the can end on the can body, and 105 as the can body and end are rotated with the support the chuck will rotate. The can end is placed on the can end seat 22, and when the can body is raised up through the opening 23, it will be centered and rounded 110 up so as to engage the can end.

In order to facilitate the stripping of the can end from the chuck after the end has been clenched to the body, I have provided knock-out pins 30. There are several of 115 these pins which extend through the chuck and rotate with the chuck. Each pin is provided with a collar 31 and a spring 32 bearing against the collar normally forces the pins downwardly so that their lower ends 120 project below the lower face of the chuck. These springs will allow the pins to yield when the rotating support is moved upwardly, and the can is brought into engagement with the face of the chuck.

As clearly shown in Fig. 2 of the drawings, the rotating carrier is provided with six filling devices and six rotating supports for the cans. The empty can bodies are fed into the machine by means of a timing de- 125 130

vice which is indicated at T in Fig. 1 of the drawings. Said timing device includes a traveling chain 33 having spread fingers 34 which engage the empty can bodies and feed 5 the same forward onto the rotating carrier in proper timing so that the cans will move onto the rotatable supports and be centered thereon by the half-mold guiding sections 25. At the point indicated at α in Fig. 2 10 of the drawings, the can body has been placed underneath the nozzle of the filling machine and the cam groove 28 is shaped so that the valve is being withdrawn from this point on until the point γ is reached, when the 15 valve is fully open. When the point α is reached, the valve is fully closed. When the valve is open, the filling device discharges into the empty can and fills the same. The gear 8 for rotating the gears 7 20 is in the form of a segment so that the can bodies are not rotated during the filling operation.

The can ends are fed to the machine by means of a can end feeding mechanism and 25 can end marking mechanism, indicated at F in Fig. 1 of the drawings. The can ends are placed in a stack holder 35 (see Figs. 1 and 8). This stack holder is mounted on a suitable support and rotating underneath 30 the stack holder is a can end feeding disk 36 which is formed with a series of projecting arms 37 having ledges which engage the can ends and carry them forward. The can ends are moved forward on a support 35 38. The can ends in the stack are normally held supported by means of a sustaining lip 39 (see Figs. 8, 9 and 10), and a movable supporting member 40. This movable supporting member 40 is retracted and allows 40 the stack to drop so that the lowermost can end drops into the path of movement of the ledge 37 on the can end feeding disk. The supporting member 40 moves forward and separates the lowermost can end from 45 the stack and raises the stack, (as clearly shown in Fig. 13) so as to release this lowermost can end. In Figs. 9 and 10 of the drawings, the can ends are indicated at e , while the lowermost can end which is re- 50 leased is indicated at e' .

The can ends, as above noted, are carried along the can end support 38. Associated with this support 38 is a yielding finger 41 which engages one side of the can end, 55 and just as the can end passes this finger, owing to the round edge of the can end, it will be forced forward away from the ledge 37 on the can end feeding disk, as clearly shown in Fig. 1 of the drawings. This forward movement of the can end brings the front edge of the can end against a yielding finger 42. The finger 42 will hold the can end from movement with the can end feeding disk until the ledge 37 again comes 60 against the can end. This gives a momen-

tary dwell to the can end. During this dwell the can end is marked. The marking of the can end is accomplished by means of opposed dies, indicated at 43 and 44. The die 43 is carried by a lever 45 which is 70 pivoted at 46 to the supporting frame, and this lever carries a roller 47 at its lower end which engages a rotating cam 48. The member 44 is carried by a slide 49 and this slide 49 carries a roller 50 which co-operates 75 with a cam 51. As these cams rotate, they cause the dies to grip the can end while it is stationary and impress a suitable identifying mark or character therein. After which they release the can end, and this allows the can end feeding disk to again pick up the can end and move the same forward. This can end feeding mechanism and marking device *per se* forms no part of the present invention, and further disclosure thereof is not thought necessary. 80

As above noted, the rotating carrier is provided with a series of can end seats, one for each rotating support. The feeding disk for the can ends, moving the can ends along 90 their support, forces the can ends onto these can end seats, and thus transfers the can ends onto the rotating carrier. As above noted, the can end is fed onto the carrier after the can has been filled. After the can end has been placed on the carrier further rotation of the carrier brings the roller 10 into the section of the cam groove 12 which raises the rotating support. The upward movement of this support carries 95 the can body against the can end, and then the can end against the chuck and this seats the can end in the can body. As soon as the can end is well seated in the can body, then the gear 7 comes into engagement with 100 the rack gear 8 and rotates the filled can clamped between the support 5 of the chuck.

The rotating can may then be brought into engagement with a series of clenching rolls. The clenching mechanism is indicated at M in the drawings, and as herein shown consists of a series of rolls 52, 53 and 54. One of these rolls is shown in detail in Fig. 7 of the drawings. The roll has a curling groove 55 which engages the edge 110 of the can ends, indicated at E in this figure of the drawings, and rolls it around the flange f on the can body B. The roll is mounted on a suitable support which may be adjusted by means of an adjusting screw 115 56. This clenching mechanism *per se* forms no part of the present invention, and has been shown particularly for the purpose of illustrating one way of clenching the can ends on the can bodies. It will be understood that other clenching devices may be used. These clenching rolls are so disposed relative to each other that the can in passing from one roll to the next roll will be 120 given a partial rotation so that the can end 130

is clenched to the can body at three points which are substantially the same distance apart.

After the can end has been clenched to the can body, the rotating support is lowered through the action of the cam groove 12 and the knock-out pins strip the closed can from the chuck. A guide 57 extends from the rotating carrier and serves as a stripping means for stripping the closed can from the carrier. In Fig. 1 of the drawings, the double seaming machine is illustrated which is indicated at S. This double seaming machine is provided with a rotating drum 58 and the closed cans are received by this drum which carries them forward into the seaming machine where the ends are double seamed onto the can bodies.

In Figs. 15, 16 and 17 of the drawings, I have shown another form of means for securing the can end to the can body. In this form of the invention the support for the filled can 5 is similar in construction to that above described. The can body is centered on the support by the bracket 25; the can end is placed in the can end seat in the plate 21, and the opening through this plate is tapered, as indicated at 23, so as to round up the can body and cause it to properly engage the can end. The further lifting of the can body and can end causes the can end to be seated against the rotatable chuck 17. Prior to the placing of the can end on the seat, the valve 26 was, of course, opened so as to permit the contents of the can to pass down through the nozzle 14 into the can. As above noted, the support 5 for the can is rotated, and this rotates the can body and can end together with the rotatable chuck 17. While the can is being rotated, the seaming rolls are brought into engagement with the flange on the can end for rolling the same into a seam with the flange on the can body. The seaming rolls are indicated at 60 and 61 in the drawings. These are first and second operation seaming rolls. The seaming roll 61 is carried by a lever 62 which is pivoted at 63 to the head of the machine, and this lever is moved back and forth by means of an operating cam 64 carried on the sleeve 65 which freely engages the outer wall of the nozzle. The seaming roll 60 is carried by a lever 66 which is pivoted at 67, and this lever is moved to bring the seaming roll into engagement with the flange on the can end by a cam 68 which is also carried by the sleeve 65. The sleeve 65 has spaced projecting ribs 69 and 70 between which a cam rail 71 fixed to the plate 29 extends. This cam rail is shaped so as to move the sleeve 65 up and down in proper timing for bringing first one seaming roll and then the other into engagement with the can end in a manner well-known in this art, and the rotating of the can end and the can body causes the double

seam to be formed. It will be understood that the operation of the seaming rolls occurs during a partial rotation of the carrier. After the can end has been secured to the can body the seaming rolls are retracted, the support 5 drops, and the knock-out pins 30 strip the closed can from the chuck and it is later removed from the machine.

From the above disclosure, it will be apparent that I have provided a machine wherein the empty can bodies are placed on a rotating support which rotates continuously. After the empty can is once placed on the support, it is not movable laterally relative to the support until it is filled, the can end placed thereon, and secured to the can body. It is well known that any sudden change in the lateral movement of the can body while it is being filled is liable to spill the contents thereof. If it is moving it should be kept moving, and if it is stationary it should be kept stationary. The can body in my machine is moving with the carrier and without changing in any way the speed of movement it is filled and closed.

It will be further noted that in my improved machine the can bodies are received in succession one after the other by the rotating carrier which is equipped with a plurality of filling devices. A single can end feed supplies the rotating carrier with can ends, and these cans after they are filled and the ends applied thereto are closed either by the single clenching device operating upon the cans one after the other or by the seaming rolls which are associated with the filling nozzle.

While I have described the placing of a can end on a can body, it will be understood that I have used the can end broadly as defining any covering means for the can, and it will also be understood that I have used the term "securing means" throughout the claims as defining any clenching of the can end onto the can body or the seaming of the can end onto the can body.

It is obvious that minor changes in the details of construction and the arrangement of parts may be made without departing from the spirit of this invention as set forth in the appended claims.

Having thus described the invention, what is claimed as new is:—

1. The combination of a can support, a chuck coöperating with said can support, means for filling a can while on said support through said chuck, means for placing the can end over the can after it is filled, and means for seating the can end in the can and for securing the can end to the can.

2. The combination with a rotatable can support, a rotatable chuck coöperating with said can support, means for filling a can while on said support through said chuck, means for placing a can end over the can

after it is filled, and means for seating the can end in the can and securing the can end thereto.

3. The combination of a rotating carrier, a can support mounted thereon, a chuck over said can support, means for placing an empty can on the can support, means for filling the can through said chuck, means for placing a can end over the can after it is filled, means for raising the can support for seating the can end in the can and clamping the same against the chuck, means for rotating the can support, and means for securing the can end to the can.

15 4. The combination of a rotating carrier, a plurality of can supports carried thereby, a filling device associated with each support, a chuck associated with each support and having an opening therethrough through which the can is filled, means for placing the can on each support, means for operating the filling device so as to fill the can during a partial rotation of the carrier, means for placing a can end over the can after it is filled, and means for securing the can end to the can while on said support.

5. The combination of a rotating carrier having a plurality of can supports, a supporting plate above said can supports having tapered openings in line with the can supports and a can end seat at the upper face of each opening, a rotatable chuck above each opening in the plate, filling devices for filling the cans through the chucks, means for placing a can end on its seat after the can is filled, means for raising the can support for causing the can to engage the can end and clamp the same against the chuck, means for rotating the can support and chuck, and devices operating to secure the can end to the can.

6. The combination of a rotating carrier

having a plurality of can supports, a supporting plate above the can supports having openings in line with each support and a can end seat at the upper face of each opening, a can body guide carried by the plate for positioning the cans underneath the openings in the plate, means for placing the empty cans on the carrier while it is rotated, a rotatable chuck above each opening, each chuck having an opening therethrough, a filling device associated with each chuck for filling the cans beneath the said openings, means for controlling the filling devices whereby the cans are filled in succession and during a partial rotation of the carrier, means for placing a can end on the seat after the cans are filled, means for raising the can supports for causing the can to engage the can end and clamp the same against the chuck, means for rotating the supports and the cans, and means for securing the can ends to the cans as they are rotated.

7. The combination of a rotating carrier, a plurality of can supports carried thereby, means for placing empty cans on the supports one at a time as the carrier rotates, a can end support associated with each can support, a filling device associated with each can support, a rotatable chuck carried by the filling device and having an opening through which the cans are filled, means for feeding a can end from a stack onto the can end seat, and means for seating the can end in the can, rotating the can, and securing the can end to the can while on said support.

In testimony whereof, I affix my signature, in the presence of two witnesses.

E. KENNETH NORTON.
